Primary Examiner — Mark A Goodwin

(74) Attorney, Agent, or Firm — Wood Herron & Evans
LLP(57) **CLAIM**

The ornamental design for a cold milling machine, as shown and described.

DESCRIPTION

FIG. 1 is a front left perspective view of my new cold milling machine design;

FIG. 2 is a left side elevation view thereof;

FIG. 3 is a front right perspective view thereof; and,

FIG. 4 is a right side elevation view thereof.
